Aaron Parsons, of Buckfield, State of Maine

Letters Patent

The schedule referred to in these Letters Patent and making part of the same containing a description in the words of the said Aaron Parsons, him self of his "Improvement in the Machine for Threshing and cleaning grain."

To all to whom these presents shall come,

Be it known that I, Aaron Parsons of Buckfield in the County of Oxford aforesaid of Maine, have invented a new and useful improvement in a Machine for threshing and cleaning grain, and that the following is a full and exact description thereof.

1. I construct a frame, about 6' a foot long, two feet wide, and three feet high. Near one end of said frame a concave about one fourth of a circle, extending across the frame, confined to the same by iron bolts. in said concave I place four rows of teeth about one inch apart in the row.

2. Above said concave I place a cylinder with four rows of teeth (more or less) so that when the cylinder revolves the teeth, in the cylinder, shall pass between the teeth in the concave.

3. On the right-hand end of the shafts of the above named cylinder, I place a pulley, about six inches in diameter (more or less according to the speed of the power applied) on the left hand I place a pulley 6 inches in diameter, between this, and the frame I place a pulley about 8 inches diameter.

4. Just forward of the cylinder, I place an iron shaft sufficiently long to receive a pulley on each end, outside the frame, on the left hand end, I place a pulley about eight inches in diameter, on the other end I place a pulley, about four inches in diameter. On this shaft within the frame I place three other pulleys, four inches in diameter, one in the middle and the other just within the frame.

5. about 6' from the frame, about two feet and six inches from this shaft, I place a similar shaft with three pulleys on the inside of the frame, and one on the right hand end outside the frame.

6. Around these shafts and pulleys I put an iron frame, formed of wires, place one half inch apart extending across the inside of the frame, connected at each

end and supported in the middle by leather belts, the use of this sieve is to separate the straw from the grain, and is denominated the straw sieve, and is put in motion by a belt passing round the pulley on the left hand end of the shaft, (named in the fifth specification) and the small belt on the left hand end of the main cylinder shaft, (named in the fourth specification) said belt must be crooked.

8. Immediately forward of the concave across the frame I place an iron shaft, on the right hand end, of which I place a pulley about eight inches in diameter; on the other end, I make a crank, on said shaft within the frame I place a roller or cylinder three inches in diameter, across the frame, about three feet from said cylinder I place a roller one inch in diameter.

9. Around these rollers I pass a belt or a frame the whole width of the inside of the frame. The use of this belt or frame is to receive the grain as it passes through the straw sieve and convey it to the sieve hereafter named. This belt or frame is moved by a belt passing round the pulley named in the eighth specification, and the second pulley named in the fifth specification.

10. Under the last-named roller, I place a frame with grooves to contain two sieves which are put in motion by a sweep passing from said frame to the crank, named in eighth specification.

11. About the sieve last-named, I place an outlet sieve similar to that named in the seventh specification. This last sieve is moved by a belt passing from a pulley on the right hand end of one of the shafts, to the pulley named in the eighth specification on the outside of the frame.

12. Under the sieve above named, I place a rotary frame moved by a belt passing from a pulley on the left hand end of the shaft, of said frame, to the large pulley, on the left hand end of the main cylinder shaft, named in the fourth specification the wind of said frame passes through the sieve above named;

13. Under the sieve I place a slide or fine sieve to convey the grain into chutes, placed just forward of the saw.

14. Immediately forward of the main cylinder I place a slide or elevator placed at an elevation of 30°. degrees.

15. Over this whole frame I place a roof or bonnet. The machine is put in motion by horse or water power with a belt passing round the pulley on the right hand end of the main cylinder. All the above proportions of length -

breadth, height 4 $\frac{1}{2}$ may be various to be any relative proportion necessary and convenient. Several parts of the above machine as above specified are necessarily included in the above specification, which I do not claim as my own invention.

All that I claim as my own invention are the straw scisses for separating the straw from the grain, and the peculiar manner of applying the other parts of the machine, to the uses above named, the other parts included in my machine for the useful operation thereof, are described in the above specification, for a proper and full explanation thereof.

In testifying that the above is a true specification of my invention, as above described, I have hereunto set my hand this twenty second day of June in the year of our Lord one thousand eight hundred & thirty six.

Witness,

Benj. Spalding, Jr.
Samuel H. Brown,
